UNITED STATES PATENT OFFICE.

FRANK W. SHUELL, OF DETROIT, MICHIGAN, ASSIGNOR TO EVERHOT HEATER COMPANY, OF DETROIT, MICHIGAN, A CORPORATION OF MICHIGAN.

WATER HEATER.

Application filed February 4, 1924. Serial No. 690,613.

The invention relates to water heaters of that type in which the heating flame is arranged beneath the end of a cylindrical tank, the products of combustion from said flame passing upward around the walls of the tank between the same and a surrounding jacket. With such construction it is desirable to hold the hot gases in close contact with the walls of the tank so as to secure the greatest efficiency in transferring the heat. On the other hand, it is equally important to avoid interference with combustion and proper draft for carrying away the gaseous products. Therefore, in designing the construction the flue space between the jacket and the tank must neither be too large nor too small, but is so proportioned as to carry away the gases while maintaining contact with the surface to be heated. There is, however, a difficulty arising from the fact that as the gases cool, they decrease in volume. Thus if the cross section of the flue at the base of the tank is sufficient for the passage of the hot gases, this same section will be larger than is needed for the cooler gases at a higher point, which both diminishes the velocity and interferes with close contact or scrubbing action.

It is one of the features of the present invention to avoid this defect by a construction in which the cross section of the flue is diminished for the cooler gases. It is a further object to provide a construction of jacket which at the base will withstand the heat and is of sufficient strength to support the weight of the tank, while above the base it is of lighter weight and provides smaller flue space. Still further the invention consists in various features of construction as hereinafter set forth.

40 In the drawings:

Figure 1 is a vertical central section through a water heater of my improved construction;

Figure 2 is a similar view showing a modified construction.

A is the water holding tank, B is a cylindrical casing surrounding the base portion of the tank, being preferably formed of cast iron and being provided with a plurality of inwardly projecting lugs C for marginally supporting the tank. The casing B is suitably supported as by a base ring D, which in turn is mounted upon legs E. F is an upper jacket section, which is preferably formed of sheet metal and is supported on a ledge G

formed at the upper end of the casing B. As shown in Figure 1, the ledge G is formed by a bead projecting inwardly from the member B, but in the modified construction shown in Figure 2 there is arranged between the lower portion of the base B and said ledge a tapering or conical portion H. With either construction the flue area between the jacket and the tank at the lower end of the latter is greater than the flue area between the tank and the upper jacket section F. This will compensate for contraction in volume of the gases due to cooling and will maintain more nearly uniform velocity.

In the manufacture of water tanks one head is usually convex and is secured to the cylindrical body by an inwardly extending annular flange riveted thereto. It is not, however, possible to make both ends this way as it would be practically impossible to rivet the head last secured if the flange thereof were to extend inward. Therefore, it is the practice to arrange one head inward and the other head outward. With my construction of heater the convex or inwardly flanged head J is placed at the base, while the outwardly flanged head K is arranged at the top. However, this latter head, instead of being concave throughout its extent, is reversely dished so as to be convex, thereby resulting in greater strength to withstand internal pressure and also diminishing the gas pocket, which would otherwise be formed at the top of the tank.

To produce the highest efficiency the jacket is surrounded with heat insulating material, which in turn is enclosed within an outer jacket. To retain the two jackets and the tank in concentric relation, there is provided at the top a metal cap L, which is stepped or offset at M to form a bearing for the jacket F and is provided with a peripheral flange N for engaging the outer jacket O. The cap L centrally engages the nipple P which forms the outlet for the hot water, and this also holds said cap in concentric relation to the tank.

To protect the flame from drafts a bottom head or shield is arranged therebeneath, but provision must be made for admission of air to support combustion. It is also desirable to arrange the admission ports in such a manner as to conceal the light from the flame. This I have accomplished by providing the base ring D with a depending

flange D' which is surrounded by a flange Q extending upward from the cap or shield R. Thus the air which is admitted to the combustion chamber passes upward around the flange Q and downward between the same and the flange D', while the overlapping of said flanges forms a light shield.

With the construction as described, the cast iron base B, together with the ring D and legs E, forms a substantial support for the tank and will also withstand the heat of the combustion chamber. Furthermore, the space between the casing B and the lower end of the tank is sufficient for the passage 15 of the gaseous products of combustion without interference with the flame. Above the upper end of the casing B the sheet metal jacket F is sufficient to retain the cooler gases and on account of the diminished diameter of this portion of the jacket, the flue space is contracted so as to compensate for the contraction in volume of the gases. After the gases pass over the top of the tank, they again impinge against the convex por-

tion of the head K and finally escape 25 through the vent flue S. The space between the jackets G, F and O is filled with suitable heat insulating material, so that the greater part of the heat in the gaseous products is communicated to the tank and is utilized in 30 heating the water.

What I claim as my invention is:

In a water heater, the combination with a vertically arranged cylindrical tank, of a casing formed of cast metal having inwardly extending lugs for engaging and supporting said tank, said lugs being fashioned to guide said tank into concentric relation with said casing, a sheet metal jacket extending upward from said casing and surrounding 35 said tank, an outlet conduit from said tank arranged at the center of the upper end thereof, and a metal cap apertured for the passage of said outlet and engaging the upper end of said jacket to hold the same 40 in concentric relation to the tank.

In testimony whereof I affix my signature.

FRANK W. SHUELL.
